CHESSBOARD

Yun Wing Gee, New York, N. Y.

Application February 9, 1954, Serial No. 28,934

Term of patent 14 years

(Cl. D34—5)

To all whom it may concern:

Be it known that I, Yun Wing Gee, a citizen of the United States of America, residing at New York, in the county and State of New York, have invented a new, original, and ornamental Design for a Chessboard, of which the following is a specification, reference being had to the accompanying drawing, forming part thereof.

The drawing is a plan or face view of a chessboard embodying my new design.

The game board is of conventional thickness.

I claim:

The ornamental design for a chessboard, substantially as shown and described.
